UNITED STATES PATENT OFFICE.

BERNARD ARTHUR BEHREND, OF NORWOOD, OHIO, ASSIGNOR TO
BULLOCK ELECTRIC MANUFACTURING CO., A CORPORATION OF
NEW JERSEY.

SUPPORT FOR FIELD-WINDINGS.

SPECIFICATION forming part of Letters Patent No. 759,210, dated May 3, 1904.

Application filed December 7, 1903. Serial No. 184,041. (No model.)

To all whom it may concern:

Be it known that I, BERNARD ARTHUR BEHREND, a citizen of the United States, residing at Norwood, in the county of Hamilton and State of Ohio, have invented certain new and useful Improvements in Supports for Field-Windings, of which the following is a full, clear, and exact specification.

My invention relates to dynamo-electric machines, and particularly to that type in which revolving field-magnets are used, such as alternating-current machines, and is especially useful for high-speed machines.

Ordinarily and for the usual speeds of rotating field-magnets the pole tips or shoes are relied upon to keep the coils in place and to overcome centrifugal force acting on the coils. Although such means are usually sufficient for moderate speeds, some additional support is necessary for high speeds, as the strains due to centrifugal force become excessive.

The object of my invention is to provide a construction which will be simple in form, of comparatively light weight, easily assembled, and which will serve to effectively counteract the centrifugal force and relieve the windings from harmful strains and prevent their displacement.

My invention will be understood from the following description and accompanying drawings, and the novelty thereof will appear from the claims.

Figure 1 is a diagram of forces acting upon the windings. Fig. 2 is an end view of a rotating field structure with the shaft in section. Fig. 3 is a section on the line 3 3 of Fig. 2 with the shaft and collector-rings in full. Fig. 4 is a plan view of my improved coil-support detached from the machine. Fig. 5 is a sectional view on line 5 5 of Fig. 4. Fig. 6 is a plan view of a modified form of coil-support. Fig. 7 is a sectional view on the line 7 7 of Fig. 6. Fig. 8 is a plan view of another modified form of coil-support, and Fig. 9 is a section on line 9 9 of Fig. 8.

Fig. 1 shows in diagram a four-pole revolving field, the center being indicated at O. If A B represents the centrifugal force acting

upon a portion of the winding located at A, then resolving this into two components, one, 50 A D, parallel with the pole considered, and the other, A C, at right angles thereto, it is apparent that the component A C is very considerable in magnitude and nearly equals the component A D. The latter component, however, is directed against the pole-tips or pole-shoes, and the winding therefore is not displaced or strained due to this component. The component A C, however, acting at right angles to the poles and being equal on opposite 60 sides thereof, subjects the winding to a considerable strain, which tends to distort and burst the same. Considering another portion of the winding at A', a greater distance from the center O than is A, the centrifugal 65 force being proportional to the radius may be represented by line A' B' and its two components as A' D' and A' C'. Although this component A' D' is much greater than A' C', it is apparent that A' C' is about equal to A 70 C and of considerable magnitude. By my invention I provide an additional support for the windings, which opposes any strain upon them due to the component of the centrifugal force which acts at right angles to the length 75 of the pole.

Referring to Figs. 2 to 5, inclusive, the shaft of a revolving field structure to which my invention is applied is indicated at 1 and is provided with the enlarged portion 2, against 80 which rests the end plate 3. The laminae of the core are shown at 4, and these are clamped between the end plate 3 and end plate 5 and locked in place by the nut 6, threaded on the shaft. The poles are shown built up of laminae 7, clamped between the plates 8, and may be secured to the core in any suitable manner, such as by dovetailing.

The windings on each pole are made up of two parts—an outer part 9 and an inner part 9'. The poles are provided with the tips 10, and the side plates 8 are provided with the flanges 11, which serve to retain the coils on their cores. The coils rest upon the main core of the machine and are supported at the 95 sides by the cover-plates 12, secured by screws

13 to the main core of the structure. Although the laminae 4 and cover-plates 12 are shown square in general outline, they may of course be of any form and carry as many poles as 5 desired.

Between the coils 9 and 9' of each pole and surrounding the core lies a closed flat sheet of metal 14. This may have any desirable width or thickness, and in the form shown its general width is equal to the depth of the winding. The two opposite sides which extend parallel with the shaft have integral therewith the plates 15, and these extend at right angles to the plate 14 above and below the same in a 15 plane parallel with the shaft. The plates 15 are strengthened by the main ribs 16 and the radial ribs 17. The inner faces of the plates 15 are provided with the projections 18, which may be filed, so that when the support is in 20 place it closely engages the windings. Perforations 19 are formed in the plates 15 to reduce the weight of the same. The ends 20 of the plates are made tapering, as shown in Fig. 3, and may be turned around the windings 25 slightly, as shown in Fig. 4, to increase the strength of the support on the line where plate 15 joins the plate 14.

The coils may of course be connected up in series or parallel, as desired. In the present 30 instance the coils are connected in series, and the leads 21 are connected to the usual slip-rings 22.

In assembling, the coils 9 9' and supporting-plates are placed upon the field-poles, which 35 are then secured to the main core and the cover-plates 12 attached. If the poles are provided with removable pole-shoes, the coils and supporting-plates may be slipped over the poles after the latter have been secured to the 40 main core.

From the foregoing it is apparent that the windings are not only well supported between the pole-tips and flanges 11 and the main core and cover-plates 12, but the additional plates 45 15 will relieve the windings from excessive strains and also serve to protect them. The encircling plate 14, owing to its form, can have great strength and also occupy but little space. The support is preferably made of brass, phosphor-bronze, or aluminium-bronze to avoid 50 magnetic leakage.

A modified form of support is shown in Figs. 6 and 7. In this case the plate 14 is used the same as in the construction already 55 described, and instead of having plates 15 only on opposite sides of the windings a continuous enveloping sheath 23 is used. The inner face of this sheath is provided with projections 18, which closely fit the coil. The 60 sheath may, if desired, have perforations formed therein for the purpose of reducing the weight.

Figs. 8 and 9 show another modification in which the plate 14 is enlarged at opposite 65 sides, as shown at 24, and narrow plates or

extensions 25 are formed on each side of the plate 14. These extensions are spaced from each other and are reinforced by the ribs 26.

It is evident that various changes may be made without departing from the essential 70 features of my invention, and I am not limited to the exact construction shown.

I claim as my invention—

1. In a dynamo-electric machine, the combination of a field-frame, a divided field-winding on each pole thereof, and a support for the winding, comprising an inner portion located between parts of the winding and an outer portion engaging the exterior of the winding. 75

2. In a dynamo-electric machine, the combination of a field-frame, a divided field-winding on each pole thereof, and a support for the winding, comprising an inner portion located between parts of the winding and encircling the pole, and an outer portion engaging the exterior of the winding. 85

3. In a dynamo-electric machine, the combination of a field-frame, a divided field-winding on each pole thereof, and a support for the winding, comprising an inner plate located 90 between parts of the winding and an outer portion engaging the exterior of the winding.

4. In a dynamo-electric machine, the combination of a field-frame, a divided field-winding on each pole thereof, and a support for the winding, comprising an inner plate located between parts of the winding and encircling the pole, and an outer portion engaging the exterior of the winding. 95

5. In a dynamo-electric machine, the combination with the field-poles and the winding thereon of a support for the winding of each pole, comprising a portion within the field-magnet structure and an outer portion engaging 100 the exterior of the winding.

6. In a dynamo-electric machine, the combination with the field-poles and the winding thereon of a support for the winding of each pole, comprising a portion within the field-magnet structure and encircling the pole and an outer portion engaging the exterior of the winding. 110

7. In a dynamo-electric machine, the combination with the field-poles and the winding thereon of a support for the winding of each pole, comprising a plate within the field-magnet structure and encircling the pole and an outer portion engaging the exterior of the winding. 115

8. In a dynamo-electric machine, the combination with the field-poles and the winding thereon of a support for the winding of each pole, comprising a portion within the field-magnet structure and outer portions at right angles to said inner portion and engaging the exterior of the winding. 120

9. In a dynamo-electric machine, the combination with the field-poles and the winding thereon of a support for the winding of each 125 130

pole, comprising a plate within the field-magnet structure and outer portions at right angles to said inner portion and engaging the exterior of the winding.

5 10. In a dynamo-electric machine, the combination with the field-poles and the winding thereon of a support for the winding of each pole, comprising a plate within the field-magnet structure and encircling the pole, and outer 10 portions at right angles to said inner portion and engaging the exterior of the winding.

11. In a dynamo-electric machine, the combination with the field-poles and the winding thereon of a support for the winding of each 15 pole, comprising a plate within the field-magnet structure and an outer sheath integral with said plate and enveloping the winding.

12. In a dynamo-electric machine, the combination with the field-poles and the winding 20 thereon of a support for the winding of each pole, comprising a sheath enveloping the winding and a central plate integral therewith, said plate encircling the pole and located within the field-magnet structure.

25 13. In a dynamo-electric machine, the combination with the field-poles and the winding thereon of a support for the winding of each pole, comprising a plate within the field-mag-

net structure and outer plates at right angles thereto and integral therewith engaging the 30 exterior of the winding.

14. In a dynamo-electric machine, the combination with the field-poles and the winding thereon of a support for the winding of each pole, comprising a plate within the field-magnet structure, and outer plates at right angles thereto and integral therewith, said outer plates having projections which engage the exterior of the winding.

15. In a dynamo-electric machine, the combination of a shaft, a core thereon, poles on said core, a divided winding on each of said poles, cover-plates on each side of the core and supporting said windings, and a support for the winding on each pole, comprising an inner plate encircling the pole and located between the parts of the winding and outer plates integral therewith and engaging the exterior of the winding.

In testimony whereof I affix my signature in presence of two witnesses.

BERNARD ARTHUR BEHREND.
